INVENTOR
H. D. Adams

UNITED STATES PATENT OFFICE.

HALE D. ADAMS, OF GALESBURG, ILLINOIS.

OPERATING MEANS FOR AUTOMOBILE ACCELERATORS.

Application filed March 7, 1923. Serial No. 623,409.

To all whom it may concern:

Be it known that I, HALE D. ADAMS, a citizen of the United States, residing at Galesburg, in the county of Knox and State 5 of Illinois, have invented certain new and useful Improvements in Operating Means for Automobile Accelerators, of which the following is a specification.

My invention relates to means adapted 10 to be actuated by foot pressure, for regulating the intake of fuel from a carburetor to the manifold of a multi-cylinder gasoline engine; and it especially relates to a foot operated device adapted to be installed in 15 connection with the manually operated intake regulator of the standard Ford automobile engine, or of engines similarly equipped.

The accompanying drawings show the 20 parts and the manner of installation and operation of my device. In these drawings, Fig. 1 is a perspective representation of my operating means, mounted in and under the floor of a Ford automobile; Fig. 2, a top 25 view of my intermediate rocking crank shaft and its connections; Fig. 3, an end view of the same parts; Fig. 4, a top view of the carburetor and throttle arm with its usual connecting rod, before installing my device; 30 Fig. 5, the same view with certain parts of my device mounted on the carburetor; Fig. 6, an elevation of the carburetor and the parts mounted thereon; and Fig. 7, an end 35 view of the carburetor and adjacent mechanism.

Each reference character used is always applied to the same part in the drawings and in this specification.

The floor boards, 1 and 2, of a Ford automobile, are shown partly cut away to reveal 40 the manner of mounting my device. 3, 4 and 5 are the usual controlling pedals of the engine; 6 is a part of the transmission cover, provided with the usual removable plate, 7; 45 8 is the fuel inlet pipe and 9 is the exhaust pipe of the engine; 10 is the gasoline supply pipe, connecting, through coupling 10^a, with carburetor 11, in the usual manner; 11^a is the flange by means of which carburetor 11 is connected to inlet pipe 8, these 50 parts being held together by bolts, 11^b, 11^c; 12 is the standard throttle arm, provided with its regular adjusting screw, 12^a, and securely mounted, as usual, on stem 13 of 55 butterfly throttle valve 14. A hole, 15, through throttle arm 12, at its outer end,

receives the hooked end, 16^a, of rod 16, connecting arm 12 with the well known, manually operated intake regulator, at the steering wheel.

All of the parts so far described are included in the standard Ford construction and assembly.

My improved foot operated throttle control is constructed and attached as follows. 60 A bridge plate, 17, is placed somewhat above the upper end of valve stem 13, and is supported rigidly at right angles to said stem by means of posts 17^a and 17^b; held by bolts 11^b and 11^c, already described. The 65 plate 18, of substantially bell-crank form, is pivoted at 19 to bridge plate 17, the axis of pivot 19 being in alignment with the axis of valve stem 13. Plate 18 has a flange bent 70 downward and formed into a finger, 18^a, 75 adapted to enter hole 15, in arm 12, as shown in Fig. 5, 6 and 7, rod 16 with hooked end 16^a being removed from said hole 15. A part of the flange of plate 18, adjacent to finger 18^a, is provided with a slotted hole, 18^b, 80 adapted to receive rod 16 and permit same to perform its usual function, as later explained. End 20^a of connecting rod 20 is pivotally attached, at 18^c, to plate 18, and the other end of rod 20 is similarly connected with arm 21^a, of shaft 21, which is 85 mounted for oscillatory movement in bearings, 22^a and 22^b, of bearing plate 22. Beyond bearing 22^b, shaft 21 has an arm, 21^b, 90 preferably flattened as shown. Arms 21^a and 21^b, of shaft 21, are so placed that, when 95 arm 21^a is held by connecting rod 20, arm 21^b extends in a backward, sloping direction, nearly parallel with floor boards 1, 2. Bearing plate 22 is provided with a flange, 22^c, 100 adapted to be rigidly attached to transmission cover 6, by means of screws 7^a and 7^b, two of the screws that hold plate 7 in place. Spring 23 extends from a connection at end 23^a with plate 18, and is attached, at 23^b, 105 to plate 22, having sufficient tension to close throttle valve 14 and keep it closed, when not held open by one of the throttle operating means, as later explained. Pedal rod 24, 110 slideable in holder 25, is mounted in floor 2, in such position that the lower end, 24^a of said rod, normally rests upon arm 21^b and head 24^b is held somewhat above holder 25, the parts being so proportioned and placed that said head, 24^b, stands conveniently near 110 pedals 3, 4 and 5.

Pressure applied to head 24^b causes rod 24

to slide downward in holder 25, thereby applying pressure to arm 21^b, causing shaft 21 to turn in its bearings, 22^a, 22^b, and making arm 21^a swing toward carburetor 11. Connecting rod 20, moving with arm 21^a, causes plate 18 to turn on pivot 19, spring 23 yielding to the strain brought upon it and being stretched thereby. This movement of plate 18 acts upon arm 12, through finger 18^a, in hole 15, opening valve 14, more or less, according to the amount of motion communicated to pedal rod 24, at the will of the operator. Spring 23 closes valve 14 when the pressure upon head 24^b is withdrawn, unless prevented by rod 16 being or having been placed in valve opening position by use of the manually operated valve control.

Operating plate 18 and arm 12, the foot actuated means described is not interfered with by rod 16 of the manually operated valve control, when the parts of said manually operated control are allowed to remain in valve closing position, as they should be when it is desired to use the foot control. In that position, rod 16, sliding back and forth in hole 18^b, permits valve opening and valve closing movement of plate 18 as just described. The hooked end, 16^a, of rod 16 prevents the withdrawal of the rod from hole 18^b and, in case of operation of the manually actuated parts, causes plate 18 to turn on pivot 19 in the same manner as when actuated by the foot operated means described. During any movement of plate 18, even when caused by connecting rod 16, a corresponding movement of all the movable parts of the foot control system takes place, rod 20 acting upon arm 21^a, shaft 21 and arm 21^b, and pedal rod 24 sliding down or being pushed up, as permitted or required by any motion of arm 21^b.

What I claim is:—

45 1. In a device of the character described,

the combination with a fuel inlet valve controlling arm of a member adapted to operate said arm, said operating member being pivoted independently of said arm, but having the axis of its pivot in alignment with the axis of said valve controlling arm.

2. The structure specified in claim 1 and, in combination therewith, spring means adapted to return said arm operating member to its normal position for bringing said arm to its valve closing position; a down-turned flange on said arm operating member, said flange having a hole adapted to receive the connecting rod of the ordinary manually operated valve control and to allow said rod to slide back and forth in said hole during operative movement of said arm operating member.

3. A fuel intake regulating device comprising, in combination with the customary throttle valve, equipped for control by manual means, a member pivoted independently of said valve, in co-axial alignment therewith, being adapted to actuate said valve by engaging the customary arm on same; also comprising foot operated means adapted to swing said pivoted member independently of said manual means of control and further comprising spring means adapted to hold said pivoted member in valve closing position but yielding to pressure applied either manually or by foot through the means specified; said foot operating means comprising a depressible pedal rod with suitable head, a rock-shaft provided, at one end, with an arm extending under and in contact with said pedal rod, and having, at its other end, a downwardly extending arm; and a rod connecting the lower end of said second arm with said spring-held, pivoted member.

In testimony whereof I hereunto affix my signature.

HALE D. ADAMS.
